UNITED STATES PATENT OFFICE.

JAMES ANDREW McCUTCHEON, OF PINE GROVE, ASSIGNOR OF ONE-THIRD TO
WM. M. DIGHT, OF MERCER, PENNSYLVANIA.

CURTAIN-FIXTURE.

SPECIFICATION forming part of Letters Patent No. 257,826, dated May 9, 1882.

Application filed March 6, 1882. (No model.)

To all whom it may concern:

Be it known that I, JAMES ANDREW McCUTCHEON, of Pine Grove, in the county of Mercer and State of Pennsylvania, have invented 5 certain new and useful Improvements in Blind-Adjusters; and I do hereby declare that the following is a full, clear, and exact description thereof, reference being had to the accompanying drawing, and to the letters of reference 10 marked thereon, which form part of this specification, in which the invention is illustrated applied to a window frame and blind, showing the latter partly rolled up from the bottom.

This invention relates to novel means for 15 rolling up and unrolling window-blinds, and, when desired, adjusting the blind at the top to any desired height; and the nature of my invention consists in a novel system or arrangement of cords and pulleys in combination with 20 a suspended window-blind having a roller at its lower end, as will be hereinafter explained.

The following description of my invention, when taken in connection with the annexed drawing, will enable others skilled in the art 25 to fully understand it.

A designates the window-frame; B, a window-blind made of any suitable flexible material, and provided with a rigid strip, C, at the top, and a roller, C', at the bottom. To the lintel of 30 the frame I apply four grooved pulleys, D D' D' D', which may be made ornamental. These pulleys may be the ordinary vitreous knobs attached to the lintel by means of screws around which they are free to turn.

35 E designates a cord, the ends of which are secured at a a to the lintel near the two pulleys D D'. The cord E is passed through eyes b b, fixed to the top edge of the shade-strip C,

thence over the pulleys D D', thence down and around the roller C', thence up and over the 40 two pulleys D' D', thence down again in the center of the shade, through an eye, c, fixed to the head of the tassel G, where the two portions of the cord come together, and are passed freely through a guide-eye, d, fixed to the strip C 45 at the middle of the length thereof. The cord is then passed through an eye, g, fixed to the lintel centrally between the two knobs or pulleys D' D'.

It will be seen that by manipulating the 50 tassel—that is, by pulling it down or releasing it—the shade can be rolled up or unrolled. The weight of the roller and the counterbalancing-weight of the tassel G will arrest the blind at any desired point of adjustment. By simply raising the tassel the roller will unroll by 55 its own gravity.

If it is desired to admit light from above the blind, this can be done by simply pulling the blind down bodily.

Having described my invention, I claim—

The combination, with the window-blind provided with a roller and a top strip, of the pulleys D D' D' D', the cord E, fixed at a a to the lintel, passed over the outer pulleys, around 65 the curtain-roller, over pulleys D' D', through an eye or ring attached to the tassel, through the eye d and the eye g, all substantially in the manner and for the purposes described.

In testimony that I claim the foregoing as 70 my own I affix my signature in presence of two witnesses.

JAMES ANDREW McCUTCHEON.

Witnesses:

WILLIAM KILE,
JAS. MURPHY.
